DES. 2245

Henry Baier, of New York, N. Y.

Letters Patent No. 2245. Dated Jan. 30, 1866.

Design for a Centrepiece in Allo-relief.

The schedule, referred to in these Letters Patent and making part of the same.

To all whom it may concern:

Be it known that I, Henry Baier, of the City, County and State of New York, did invent a new and useful design for a centrepiece, and that the following is a full, clear and exact description thereof, reference being had to the annexed drawing, making part of this specification, representing a top view of my said improved centrepiece.

The said centrepiece consists of a central ornament, of a circular form around which are arranged four other central ornaments, B, C, D, E, and between these are placed four other ornaments, G, H, I, J, of said shape and in such a manner as to form with all the other ornaments a uniform circle around which eight other ornaments, K, L, M, N, O, P, Q, are arranged as to form a still larger circle.

What I claim as new and desire to secure by Letters Patent, is the design for a centrepiece to be executed in allo-relief, as shown and described.

Witness,

Chas. White

Henry Baier
